Patented Jan. 31, 1961

189,700

PLASTIC PAIL OR SIMILAR ARTICLE

Charles O. Bliss, 6674 Santa Monica Blvd.,
Los Angeles, Calif.

Filed Nov. 1, 1955, Ser. No. 38,674

Term of patent 14 years

(Cl. D58—17)

FIG. 1

FIG. 2

FIG. 3

FIG. 4

Fig. 1 is a side perspective view of a plastic pail showing my new design;

Fig. 2 is a top plan view thereof;

Fig. 3 is a bottom plan view thereof; and

Fig. 4 is a sectional view on a larger scale, taken on the line 4—4 of Fig. 1.

I claim:

The ornamental design for a plastic pail or similar article, substantially as shown.
